Harry S. Dimarce

ATTORNEY

UNITED STATES PATENT OFFICE

PAUL R. BROESKE, OF NORTH CANTON, OHIO, ASSIGNOR TO THE HOOVER COMPANY, OF NORTH CANTON, OHIO, A CORPORATION OF OHIO

SWITCH

Application filed June 20, 1932. Serial No. 618,155.

The present invention relates to electrical switches and particularly to means for mounting an electric switch within a hollow tubular handle, such as might be used 5 with a suction cleaner or similar apparatus, or within a box. More specifically the invention comprises the provision of new and novel switch-mounting means in which the switch is easily mounted and dismounted, 10 being held in place by resilient means when in normal position.

It is an object of the present invention to provide new and novel electrical switch 15 mounting construction. It is a further object to provide a novel construction for mounting a switch within a hollow tubular member. These and other more specific objects will appear upon reading the following specification and claims and upon 20 considering in connection therewith the accompanying drawing.

Referring to the drawing:

Figure 1 is a disclosure of the present invention embodied within a hollow tubular 25 handle which is shown partly in section;

Figure 2 is a section upon the line 2—2 of Figure 1;

Figure 3 is a view in perspective of the 30 switch mounting within a hollow tubular handle, a portion of the handle being broken away to better show the switch position therein;

Figure 4 shows a modified embodiment of 35 the present invention embodied within a tubular housing which is shown partly in section;

Figure 5 is a view similar to Figure 4 showing a still further modified embodiment 40 of the present invention.

In the drawing, and Figures 1 to 3 in particular, an elongated hollow tubular member 1 is shown provided with a longitudinally extending opening or slot 2. A cover plate 3 is provided which has the same curvature 45 as the tubular member 1 and closes the opening 2, being suitably secured to the member 1 by screws 4, 4 at its ends. A conductor 5 which includes leads 6 and 7 is carried by 50 the cover plate 3, being suitably secured

thereto by means including a strain-relief member 8 and a clamp member 9.

The switch indicated generally by the reference character 10, includes a body 11 formed of suitable insulating material, and an actuating lever 12. The switch is positioned within the member 1 in such relationship that the shoulder 14 on the body 11 securely seats within an opening 13 in the cover plate and the lever or trigger 12 extends therethru. The body 11 of the switch 10 is of such height that its side wall opposite the lever side closely approaches the enclosing tubular member 1. Between the wall and the surrounding member rubber seat 15 is positioned which is of such dimensions that with the switch in place and the cover plate 3 secured to the body 1, it is compressed thereby forcing the switch body 11 firmly against the cover plate 3 and maintaining the shoulder 14 within the opening 13. The upper wall of body 11 may be ribbed, as shown at 16, so that upon the compression of member 15 relative movement between the switch and the seat member is prevented, the outer surface of seat member 15 being curved and rounded so that it substantially conforms to the curvature of the tubular member 1. As a precautionary measure insulating the switch 11 from the surrounding metallic tubular member 1 a fibre enclosing member 17 is provided which extends the length of the body 11, being carried by the seat member 15.

Referring now to the embodiment of the invention shown in Figure 4 a switch of a slightly modified type is shown and is secured in place in a slightly different manner. The conductor 5 is secured to the cover plate 3 in the same manner as in the first embodiment. The body 11 of switch 10 is provided with a shoulder 14 of somewhat greater extent than that in the first embodiment, a detail necessary by the difference in the actuating levers 12, 12 in the two embodiments. In the present exemplification of the invention the body 11 of the switch is provided with a groove or channel 18 along its upper face which is undercut at its ends and which carries a flexible flat leaf spring 19, the ends

of which extend into the ends of the recess to prevent the dislodgment of the member. With the construction assembled the spring 19 contacts the enclosing body 1 and is compressed, the action resulting in the forcing of switch body 11 against the cover plate 3 which is itself held in place by screws 4, 4 as before. The shoulder 14 in the opening 13 in the cover plate prevents any longitudinal movement of the switch 10 and spring 19 prevents the dislodgment of shoulder 14 from its seat 13.

In the embodiment of the invention shown in Figure 5 the flat spring 19 of the embodiment shown in Figure 4 has been replaced by a coil spring 20, the ends of which extend within the undercut ends of the channel 18 in the manner of spring 19. In operation spring 20 is the functional equivalent of spring 19 and prevents the displacement of the switch 10.

I claim:

1. In a switch mounting, a hollow member having an opening on one side, a removable cover plate closing said opening, an electric conduit carried by said cover plate extending therethru into said hollow member, a switch positioned in said hollow member and connected to said conduit including a wall spaced from said enclosing member and an operating lever extended thru said cover plate, and a resilient seat member compressed between said wall and said enclosing hollow member pressing said switch against said cover plate.

2. In a switch mounting, a hollow member having an opening on one side, a removable

cover plate closing said opening and being itself provided with an opening, a switch including a rigid body positioned in said hollow member and including a portion which seats within the opening in said plate and a wall opposite said portion, and a resilient compressible member between said wall and the surrounding hollow member for the purpose of holding said switch body against said cover plate with said portion in said opening.

75

3. In a switch mounting, a hollow member having an opening on one side, a removable cover plate closing said opening and being itself provided with an opening, a switch including a rigid body positioned in said hollow member and including a portion which seats within the opening in said plate and a wall opposite said portion, a resilient compressible member between said wall and the surrounding hollow member for the purpose of holding said switch body against said cover plate with said portion in said opening, and an insulating cover seated on said resilient compressible member and extended around said switch.

90

4. In a switch mounting, a hollow member having an opening on one side, a removable cover plate closing said opening, a switch including a body and an actuating lever, said body contacting said plate and said lever extending therethru, and a compressible member comprising a spring carried by said body in contact with the enclosing hollow member for the purpose of forcing said body against said cover plate.
